CLAIM

The ornamental design for a modular architectural cistern, as shown.

DESCRIPTION

FIG. 1 is a perspective view of a modular architectural cistern showing my new design;
FIG. 2 is a top side view thereof;
FIG. 3 is a left side view thereof;
FIG. 4 is a front view thereof;
FIG. 5 is a right side view thereof;
FIG. 6 is a back view thereof; and,
FIG. 7 is another perspective view thereof.

The broken lines illustrate portions of the modular architectural cistern that do not form a part of the claimed design.
